(57) **CLAIM**

The ornamental design for a ride-on toy car, as shown and described.

DESCRIPTION

FIG. 1 is a front, right and top perspective view of a ride-on toy car, showing my new design;

FIG. 2 is a rear, left and top perspective view thereof;

FIG. 3 is a rear, right and bottom perspective view thereof;

FIG. 4 is a front view thereof;

FIG. 5 is a rear view thereof;

FIG. 6 is a top plan view thereof;

FIG. 7 is a bottom plan view thereof;

FIG. 8 is a right side view thereof;

FIG. 9 is a left side view thereof;

FIG. 10 is an enlarged view of portion of FIG. 1 thereof.

FIG. 11 is an enlarged view of portion of FIG. 2 thereof.

FIG. 12 is an enlarged view of portion of FIG. 2 thereof;

FIG. 13 is an enlarged view of portion of FIG. 2 thereof; and,

FIG. 14 is an enlarged view of portion of FIG. 3 thereof.

The broken lines shown in the drawings illustrate portions of the ride-on toy car that form no part of the claimed design.

The dash-dot broken lines are included to annotate partial views in FIGS. 1-3 and 10-14 and form no part of the claimed design.
